UNITED STATES PATENT OFFICE.

CHARLES WITTENBERG, OF INDIANAPOLIS, INDIANA, ASSIGNOR TO EDWARD G. CORNELIUS, OF SAME PLACE.

TELEPHONE-TOLL COLLECTOR AND REGISTER.

SPECIFICATION forming part of Letters Patent No. 355,744, dated January 11, 1887.

Application filed April 23, 1886. Serial No. 199,900. (No model.)

To all whom it may concern:

Be it known that I, CHARLES WITTENBERG, a citizen of the United States, residing at Indianapolis, in the county of Marion and State 5 of Indiana, have invented a new and useful Improvement in Telephone-Toll Collectors and Registers, of which the following is a specification.

My invention relates to an improved attachment for telephones, for receiving tolls for the use of the telephone, or for registering the number of times the telephone is used.

The object of my improvement is to provide means for locking the switch-lever of a telephone apparatus, whereby it becomes necessary to deposit a coin or check representing the amount of toll required, or to carry forward one point a registering-disk before the switch-lever can be moved to make the required connections to put the telephone in operation; the purpose being to have the habitual user of the telephone register the number of times that he uses the apparatus, while a transient user must deposit a coin for toll, 25 which deposit makes the register inoperative, all as hereinafter fully explained.

The accompanying drawings illustrate my invention.

Figure 1 is a front elevation. Fig. 2 is a section at *a*, Fig. 1. Fig. 3 is a section at *b*, Fig. 1. Fig. 4 is a perspective view of a detail.

A is the case, adapted to be secured to the side of an ordinary telephone-case, and containing register and toll-collecting mechanism. 35 Said case extends also across the telephone-case beneath and upward along the opposite side of the box *B*, which contains the magneto-bell apparatus and the switch-lever *C*, so as to include that portion of said switch-lever between the hook which supports the telephone-receiver *D* and the side of the box *B*.

The switch-lever *C* is locked by a catch-lever, *e*, in the position in which it is held by the weight of the receiver *D*—that is, in such 45 a position that the signal-bell is connected with the exchange, and the transmitter and receiver are disconnected therefrom. Said catch-lever is disengaged and the switch-lever released by means of a trip-lever, *f*, which is mounted on a shaft, *h*, having on its opposite end a second lever, *i*. The free end of lever *i*

is arranged in case *A*, beneath a plunger, *j*, which is supported in suitable ways, so as to slide vertically therein by a spring, *k*.

L is a bracket secured to the plunger *j* so as 55 to slide therewith.

m is a catch-bar pivoted at *n* to bracket *L*, and having its lower end adapted to engage the free end of lever *i* and its upper end adapted to engage the actuating-lever *o* of a 60 register, *R*. The arrangement of levers *i* and *o* and catch-bar *m* is such that when the lower end of the catch-bar hangs in its normal position, as shown in full lines in Fig. 2, both of said levers will be engaged by the catch-bar 65 when plunger *j* is moved downward; but when the catch-bar is swung to one side against a stop, *p*, as shown in dotted lines, Fig. 2, neither of said levers will be engaged by the catch-bar.

T is a chute arranged to conduct a coin from the top of the case to a point between plunger *j* and lever *i*.

For the purpose of giving an alarm each time that the register *R* is carried forward one 75 point, the edge of the register-disk is notched to correspond with the gradations, and said notches engage the hammer of the bell *r*.

S is a drawer arranged in the lower part of case *A*.

The operation of my device is as follows: The telephone-receiver *D* being hung on lever *C*, said lever is depressed, and the receiver and transmitter of the telephone are thereby disconnected from the line-circuit in the manner 85 common and well known. The switch-lever is automatically locked in said position by the catch-lever *e*, which hooks over the lever, as shown in Fig. 3. After the receiver has been removed from the lever, the person who habitually uses the telephone pushes plunger *j* down. Catch-bar *m* engages lever *i*, the movement of which is transmitted through shaft *h* to the trip-lever *f*, which, moving backward against the catch lever *e*, disengages said 90 lever from the switch-lever, which is drawn up, when released, by the spring *v*, thus making the connections in box *A*, which place the telephone in the line of communication. At the same time the upper end of catch-bar *m* 95 engages the actuating-lever *o* of the register, thereby moving the register forward one point, 100

When the telephone is to be used by a transient caller, he is directed to place a nickel in the chute T. The coin comes to rest on lever *i* and against the catch-bar *m*, pushing the catch-bar over into the position indicated by dotted lines, Fig. 2. The coin now forms the connection between the plunger and lever *i*, and the plunger being depressed until the coin escapes between the catch-bar and the shorter portion of the lever the lever *i* is moved and the switch-lever released, as before described, and the coin is discharged into the drawer S. If the transient caller neglects to deposit the nickel the register will be operated, and the alarm thereby given on bell *r* notifies the person in charge.

I claim as my invention—

1. The combination of the following elements, namely: a telephone switch-lever of the class shown and described, a locking device arranged to engage said lever, and mechanism for operating said locking device so as

to release the lever, said mechanism having as one of its essential elements a coin or other representative of value, all arranged to co-operate substantially as and for the purpose specified. 25

2. The combination of the switch-lever C, case A, catch-lever *e*, trip-lever *f*, shaft *h*, lever *i*, chute T, plunger *j*, and a coin interposed between said plunger and lever *i*, all arranged to co-operate substantially as and for the purpose specified. 30

3. The combination of the switch-lever C, case A, catch-lever *e*, trip lever *f*, shaft *h*, lever *i*, plunger *j*, bracket *l*, catch-bar *m*, register R, and its actuating-lever *o*, all arranged to co-operate substantially as and for the purpose specified. 35

CHARLES WITTENBERG.
